Primary Examiner — Deanna L Pratt*Assistant Examiner* — Lilyana Bekic*(74) Attorney, Agent, or Firm* — Thomas I. Rozsa(57) **CLAIM**

The ornamental design for a cell phone protector case with flower design, as shown and described.

DESCRIPTION

FIG. 1 is a front side perspective view of a cell phone protector case with flower design, showing my new design;

FIG. 2 is a rear side perspective view thereof;

FIG. 3 is front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front elevational view with the flower design attachment shown separated from the cell phone protector case for ease of illustration; and,

FIG. 10 is a rear elevational view thereof.
